GRINDING MACHINE DRIVE

Thor H. Ljunggren, Charlestown, N. H., assignor
to Bryant Chucking Grinder Company, Springfield, Vt., a corporation of Vermont

Application April 27, 1944, Serial No. 532,944

2 Claims. (Cl. 74—27)

1

This invention relates to grinding machines. One object of the invention is to provide an improved mounting for a movable carriage, which, in the case of a grinding machine, may carry either the work or the grinding wheel, this mounting facilitating traverse or feed, or both, of the grinding wheel with reference to the work.

Another object is to provide a mounting for the carriage of high sensitivity and rigidity. This is applicable both for traverse and for crosswise motion, the latter serving not only for relative feed between the tool and the work, but also when applied to grinding machines, for feeding the grinding wheel relative to a wheel dressing device when the wheel is out of grinding relation to the work and is in position where the work may be safely gaged, or removed and replaced with respect to the work holder.

A further object is to provide a mechanical drive mechanism for the traverse, which when applied to an internal grinder, will tend to prevent bell mouthing of the work.

A further object is to provide improved means for pre-setting the position of the path of motion of a carriage relative to its support.

For a more complete understanding of this invention, reference may be had to the accompanying drawings in which

Figure 1 is a front elevation of the upper portion of a grinding machine embodying the invention.

Figure 2 is a top plan view of the same.

Figure 3 is a fragmentary vertical sectional view on line 3—3 of Figure 2.

Figure 4 is a detail sectional view on line 4—4 of Figure 3.

Figure 5 is a detail sectional view on line 5—5 of Figure 4.

Figure 6 is a detail sectional view on line 6—6 of Figure 3.

Figure 7 is a detail sectional view on line 7—7 of Figure 1.

Figure 8 is a detail sectional view on line 8—8 of Figure 7, but with a portion of the worm wheel broken away.

Referring to the drawings, 1 indicates the bed of the machine which has a platform 2 projecting upwardly therefrom at one end, and a support 3 narrower than the platform projecting upwardly spaced from the platform. Secured at opposite ends in the platform 2 and the support 3, are a pair of parallel guide bars 5 and 6, which, between the platform and the support overlie the bed 1. These guide bars 5 and 6 slidably support a carriage 10, for this purpose the carriage having tubular bushings 11 and 12 seated in cylindrical

bore 13 and 14 therein. The interior bores of the bushings 12 are somewhat larger than the diameters of the bars 5 and 6 and in the space between them are placed sets of ball bearings. 5 As shown, and as preferred, one of these bars, as the bar 5, has two such sets of ball bearings 15 and 16 and the other bar 6 has a single set of bearings 17. The balls of each of these sets of bearings are each of a diameter slightly greater than the normal space between the bars and the bushings so that when the sets of ball bearings are introduced between these parts they are under compression, being loaded by such compression to a predetermined amount. The sets of ball bearings 15 are free to move longitudinally within limits. For example, the sets 15 and 16 surrounding the bar 5 have their longitudinal motions determined by end abutment rings 20 and 21 and an intermediate abutment ring 22 at opposite ends of the bushings 11. The set of ball bearings 17 may have similar motion between corresponding abutment rings 23 at opposite ends of the bore 14. Suitable collapsible and expandable corrugated dust guards 25 may be positioned between the end plates 20 and 21 and the platform 2 and support 3 as shown best in Figure 6, thus to enclose the guide bar 5 against access of foreign matter to the outer face of the bar 5 which might find access to the ball bearings. Similarly the bar 6 is protected between the platform 2 and the support 3 by similar collapsible and expandable dust guards 26. The loaded sets of bearings accurately support the carriage without lost motion, but permit it to be moved axially freely and the three sets of ball bearings furnish a three-point support for the carriage which is thus in stable equilibrium at all times.

The traversing carriage 10 supports a feed carriage 30, and for this purpose the carriage 10 is provided with upwardly extending front and rear wall portions 31, 32, within which are fixed opposite ends of a pair of supporting bars 35 and 36. Cross feed carriage 30 is supported on these bars 35 and 36 by the sets of pre-loaded ball bearings 37, 38 and 39. As preferred, one of the bars 35 carries two of these sets of ball bearings as shown in Figure 3, while the other carries a single set 39. As shown in Figure 3, the sets of ball bearings 37 and 38 may have limited axial motion between the end plates 40 and 41 and the intermediate ring 42 similarly to the mountings of the sets of bearings 15 and 16 on the bar 5. The single set of ball bearings 39 may have similar limited motion between abutment rings similar to those described for the bearing 17. This provides a

three-point support for the cross feed carriage 30 similar to the mounting of the longitudinal feed carriage 10 with respect to the bed 1. Expansible and collapsible dust guards 44 may fill the spaces between the end plates 40 and 41 and the wall portions 31 and 32, and similar dust guards 45 may be employed extending between the end plates 42 and 43 and the wall members 31 and 32.

Between the bars 35 and 36 a cross feed shaft 50 may be positioned, this being operatively connected by any suitable means, as is well known in the art, for producing forward and backward motions of the carriage 30. This feed shaft 50 may also be covered between the sides of the cross feed carriage 30 and the walls 31 and 32 of the carriage 10, as by expansible and collapsible dust guards 52 and 53 similar to the guards which protect the sets of guide bars 35 and 36 and 5 and 6.

The carriage mounting is not claimed herein but forms subject matter of a divisional application Serial No. 729,843, filed February 20, 1947, for Carriage mounting.

As shown the carriage 30 has secured thereto a grinding unit comprising a motor 60 having its armature suitably connected to a grinding wheel shaft 61 supporting a grinding wheel 62 at one end. Likewise the platform 2 may have secured thereto a work supporting unit comprising a chuck of any suitable description at 65, carried by a rotary spindle 66 journaled in a head 64 secured to the upper face of the platform 2. The rear end of the work spindle 66 may have secured thereto a V belt expansion pulley 67 of a variable drive including a belt 68 passing over a similar expansible pulley 69 on the armature shaft 70 of a motor 71 also carried on the platform 2.

Special means are provided, in accordance with this invention, for moving the carriage 10 so as to effect a relative traverse between the grinding wheel and the work, this means having for a particular object to time the motion of the carriage 10 so that adjacent the ends of the traverse it is in contact with the work during a time not substantially greater than its time of contact with intermediate portions of the length of the work. For example, if the carriage is traversed in harmonic motion as by a uniformly rotating crank and a pitman, the intermediate portion of the traverse is relatively rapid while the end portions of the traverse are relatively slow. Where such a variable speed reciprocation is employed, the end portions of the work are in contact with the grinding wheel longer than the intermediate portions and thus are ground more, resulting in the end diameter portions of the ground work being of greater diameter than the intermediate portions, this being called "bell mouthed". In accordance with the present invention a simple mechanism is provided by which the rate of motion of the traverse is much more nearly uniform than is the harmonic motion previously mentioned. As shown the traversing mechanism includes a rack bar (see Figure 3) 75 secured longitudinally in a groove 76 in the lower face of the carriage 10 and between the bars 5 and 6, and with which meshes a gear 77 secured to a shaft 78 suitably journaled in bearing bushings 79, in a portion 80 of the machine bed 1, it being evident that by turning the shaft 78 the gear 77 may be rotated, which through its engagement with the teeth of the rack bar 75, produces the desired axial motion of the grinding wheel. Such motion of the shaft 78 is

produced by the rocking of a member 81 journaled on a bushing 82 on the shaft 78 and arranged to be clutched to the shaft 78 as desired, but in order that the position of the zone of traversing motion may be regulated in accordance with the specific relations of the grinding wheel and the work in any particular set-up, means are provided by which the angular relationship between the member 81 and the shaft 78 may be adjusted as desired. For this purpose a member 85 is rockably supported on a bushing 86 surrounding the shaft 78 outwardly of the forward face of the bed 1. This member 85, as best shown in Figures 3 and 4, has journaled therein transverse to the axis of the shaft 78, an adjusting shaft 89 provided with a worm 90 meshing with a worm wheel 91 secured to the forward end of the shaft 78 as by screws 92. This member 85 has a portion 93 provided with a socket 94 within which rides a spring pressed pin 95. This pin 95, as shown in Figure 5, has a beveled outer end 96 which rides against a similarly beveled abutment 97 having a shank portion 98 seated in a perforation 99 in an arm 100 projecting from a casing 101 which straddles the member 85 and is rockably supported on either side thereof on the shaft 89. This casing member 101 has a hand wheel 102 integral therewith, the casing 101 forming a hub for this wheel, access being had to the gear 91 therein through an opening normally closed by a cover 105 secured over the outer face of the hand wheel as by screws 106. To the back face of this hub or casing 101 is secured a latch member 110 provided with a tapered nose 111 projecting rearwardly therefrom, and which may be engaged in a slot 112 through an arm 113 projecting outwardly from the rocker member 81. When the latch member is in engagement in the slot 112 the hand wheel 102 is locked to the rocker member 81, the upper portion of the hand wheel being tilted rearwardly as shown by dotted lines in Figure 3. When the wheel is in this position, the casing member and hand wheel being locked to the rocker 81, the hand wheel, through the worm and worm wheel, is locked to the forward extremity of the shaft 78, so that when the member 81 is rocked, the shaft 78 is correspondingly rocked. The upper portion of the hand wheel may be moved into the full line position of Figure 3, however, removing the latch 111 from engagement with the slot 112 and thus disconnecting the hand wheel from the rock member 81. In this position of the parts, the angular relationship between the shaft 78 and the element 85 may be adjusted as desired by turning the worm shaft 89, and when this worm shaft is adjusted to the desired position, the hand wheel may be tilted backwardly and again latched to the rock member 81, thus operatively connecting the rock member 81 to the shaft 78 in a new position of angular relationship. By this means the angular relationship between the rock member 81 and the gear 77 may be adjusted so as to adjust the limits of traverse motion of the carriage 10, and thus the position of its zone of traverse, as the rock member 81 is rocked between definite limits.

Rocking of the member 81 is effected by rotation of the crank pin 120 (see Figures 1 and 7) which is adjustable in a T slot 121 from and toward its center of rotation. The crank disk 122 and the crank arm 120 are connected to a crank pin 123 extending from an arm 124 of the rock member 81 as by means of a pitman 125 journaled at opposite ends on the pins 123 and 120.

Rotation of the crank pin 120, the throw of which is less than that of the arm 124, acting through the pitman 125, oscillates the rock member 81 and thereby produces traversing motion of the carriage 10. As this motion with a constant speed of rotation of the crank pin 120 would produce an undesirably fast traverse carriage motion in the intermediate portion of its stroke, and an undesirably slow traverse motion toward the ends of its path, provision is made in accordance with this invention for driving the crank pin 120 at a variable speed, so arranged as to slow the carriage traverse speed intermediate its ends and to speed up the traverse speed adjacent to the ends. Such mechanism is shown in Figures 7 and 8. The crank disk 122 is secured to a shaft 130 to which is keyed an elliptical gear 131 meshing with a similar gear 132 keyed to a shaft 133. Also keyed to this shaft is a worm wheel 134 with which meshes a worm 135 on a drive shaft 136. The shafts 130 and 133 with their corresponding gears are housed within a casing 140 mounted within the bed 1 and outwardly of this casing the worm shaft 136 has secured thereto a belt pulley 137 over which passes a drive belt 138 leading from any suitable source of power.

The elliptical gears 131 and 132 are so arranged angularly with respect to their shafts that the small diameter portion of the gear 132 engages the large diameter portion of the gear 131, thus driving the shaft 130 at a slow rate of speed, when the carriage 10 is in its mid position of traverse, thus producing a slower traverse than would otherwise be produced, while when the carriage 10 approaches its limits of motion, the large diameter portion of the gear 132 is driving the small diameter portion of the gear 130, thus speeding up the angular motion of the crank pin 120 and correspondingly speeding up the traverse motion of the carriage 10.

The inner traverse limit of the carriage 10 may be adjusted as desired, a micrometer stop being shown at 150 for this purpose on Figure 1, and the feed position, laterally, of the carriage 30 may be determined by micrometer feed mechanism indicated generally at 151 in Figures 1 and 2. These, however, form no portion of the present invention.

From the foregoing description of an embodiment of this invention, it should be evident to those skilled in the art that various changes and modifications might be made without departing from the spirit or scope of this invention.

I claim:

1. In combination, a carriage, a drive shaft, connections from said shaft for producing linear motion of said carriage in opposite directions, a driving member journaled on said shaft, means for turning said member angularly in opposite directions through a predetermined angular extent, a second member journaled on said shaft,

- 5 a worm shaft journaled in said second member, a worm wheel fixed to said drive shaft and engaging said worm, a locking element rockable on said worm shaft, and parts on said locking element and driving member interengaging when said locking element is in one angular position about said worm shaft to lock said members together and through said worm and worm gear to said drive shaft in a definite relation, said locking element when out of locking angular relation permitting angular adjustment between said drive shaft and second member by rotation of said worm shaft, said worm shaft having a tool-receiving portion.
